APPARATUS FOR MAKING TUBES FROM INGOTS.

1,413,605.

Specification of Letters Patent. Patented Apr. 25, 1922.

Application filed December 24, 1910. Serial No. 347,280.

To all whom it may concern:

Be it known that I, SOTARO OKANO, subject of Japan, residing at No. 24 Kino Machi, Higashi Ku, Osaka, Japan, have invented new and useful Improvements in an Apparatus for Making Tubes from Ingots, of which the following is a specification.

This invention relates to an apparatus for making tubes from ingots, and consists in a combination of a set of rolls, a pair of 10 semicircularly grooved rolls, and a mandrel the head of which terminates with an edge but is gradually rounded towards its rear part.

15 The object of this invention is to obtain tubes of steel and other metal by using comparatively small force and with simple equipment and work, thus economizing labor and expense.

20 In the accompanying drawing—

Fig. 1 shows a side view of a combination of a set of rolls with a pair of semicircularly grooved rolls.

Fig. 2 is a plan view of Fig. 1, showing an 25 ingot being formed into a tube by means of the semicircularly grooved rolls and a mandrel, as the said ingot is being forced out of the last rolls.

Fig. 3 is a side view of Fig. 2.

30 Figs. 4 and 5 are respectively plan and side views of the mandrel.

Fig. 6 shows an ingot cut with an axial slit; and

35 Figs. 7 and 8 show the same as it is reduced in thickness by successive passage between the series of rolls.

This apparatus is intended for use in carrying out a new process of manufacturing metallic tubes from ingots, consisting in 40 cutting an axial slit through an ingot, rolling the ingot to about twice the thickness of the wall of the tube to be manufactured, and forming the flat ingot into a tube by means of a mandrel and a pair of grooved rolls, 45 taking advantage of the force with which the ingot is forced out of the reducing rolls.

To describe my invention in detail, on a frame *a*, three rolls *b*, *c* and *d* are mounted which are revolved by means of toothed 50 wheels *e*, *f* and *g* through arms *h*, *i* and *j*, and are adjustable as to spaces between them according to the thickness to which the ingot

is to be rolled. The number of rolls can of course be increased to four or more if required.

55 In front of the lowest pair *c* and *d* of the rolls are mounted another pair of rolls *k* *l*, revolved by any suitable mechanism. Each of these rolls *k* *l* is semicircularly grooved, so that a circular space, the diameter of which is equal to the outer diameter 60 of the tube to be manufactured is left between them.

The mandrel is shaped something like an ax terminating at the front end with an 65 edge *m'* but gradually rounded toward the rear part *m''*, the diameter of the rounded part *m''* being equal to the inner diameter of the tubes to be made. This mandrel is fixed to a long rod *n* in such a way that the 70 rounded part *m''* lies in the circular space left between the grooved rolls, the distance between the mandrel and the rolls being equal to the thickness of the wall of the tube 75 to be manufactured.

To manufacture steel tubes with this apparatus, first cut an axial slit *p* through an ingot *q* leaving spaces *w* *w*, uncut on both sides of the slit, each equal to or a little larger than, the thickness *y* of the tube *r* to 80 be manufactured. Then roll the ingot thus cut with a slit, with the rolls *b* and *c* several times, reducing the ingot in thickness gradually to *q'*, then to *q''*, and so on, until a certain thickness is obtained, by adjusting 85 the space between the said rolls at each rolling as required. When the ingot is to be rolled for the last time, that is, to reduce the ingot to such a degree that the thickness 90 from the central slit is equal to, or a little greater than, the thickness of the wall of the tube to be manufactured, the ingot should be passed between the rolls *c* and *d*, and as it passes from the said rolls, the edge of the 95 mandrel should be inserted in the slit. Then the mandrel, which is firmly fixed, will open the flat ingot into a tube, its rounded part shaping the bore of the tube. At the same time the grooved rolls, between which the 100 ingot passes, form the outer shape of the tube. Thus, the energy with which the flat ingot is forced out of the last rolls, and over the mandrel and between the grooved rolls, will shape it into a perfect tube.

According to the process heretofore commonly used, a mandrel is forced into a solid ingot and a bore made therethrough, the ingot thus pierced with a bore, being then 5 rolled into a tube. Thus great power, and extensive mechanical and other equipment are required, which makes the work of tube making very expensive, and as a matter of fact, it is impracticable for a factory on a small 10 scale to undertake it.

However, if the apparatus of my invention is used, as an axial slit is cut through an ingot, which is then repeatedly rolled until it is reduced to the required thickness, and as 15 the ingot thus rolled and reduced is formed into a tube by a mandrel and a pair of grooved rolls, taking advantage of the force with which the ingot is forced out of the last rolls, the power and expense can be greatly 20 economized. Moreover, the work of boring an ingot and that of rolling it into a tube can be done at once, and tubes of uniform 25 quality and size can be manufactured with comparatively greater rapidity and with equipment on a smaller scale.

I wish it understood that my apparatus

can be modified in plan without departing from the spirit of my invention.

I claim:—

An apparatus for manufacturing metal 30 tubing by opening a blank having an axial slit by means of a mandrel, comprising a pair of rolls adapted to roll the blank into any desired thickness and at the same time to push the same against the mandrel, a 35 mandrel having a sharp edge at its forward end corresponding approximately with the size of the slit and tapering to a circular section at its rear end corresponding with the interior of the tube to be formed, and a pair 40 of semicircularly grooved shaping rolls having the groove radius equal to the radius of the tube to be formed, said two pairs of rolls being disposed axially perpendicular to each other.

In testimony whereof I have signed my name to this specification in the presence of two subscribing witnesses.

SOTARO OKANO.
